DISH DRAINER

Clyde D. Keaton, Woodstown, N. J.

Application December 30, 1948, Serial No. 150,450

Term of patent 14 years

(Cl. D44—29)

To all whom it may concern:

Be it known that I, Clyde D. Keaton, a citizen of the United States, residing at Woodstown, county of Salem, State of New Jersey, have invented a new, original, and ornamental Design for Dish Drainer, of which the following is a specification, reference being had to the accompanying drawing, forming part thereof.

Fig. 1 is a plan view of a dish drainer, showing my new design;

Fig. 2 is a side elevational view of the dish drainer shown in Fig. 1;

Fig. 3 is an end view of the drainer shown in Fig. 1; and

Fig. 4 is a sectional view along line 4—4 of Fig. 1.

I claim:

The ornamental design for a dish drainer, as shown.

CLYDE D. KEATON.
